UNITED STATES PATENT OFFICE

2,474,310

ELECTRICAL CONNECTOR

Hallan E. Goldstine and Oswin F. Voigt, Port Jefferson Station, N. Y., assignors to Radio Corporation of America, a corporation of Delaware

Application March 22, 1944, Serial No. 527,596

3 Claims. (Cl. 173—269)

1

This invention relates to a new and useful electrical connector which is particularly adapted for making connections to high frequency apparatus.

An object of this invention is to provide a simplified and improved electrical connector.

Another object of this invention is to provide an electrical connector having low contact resistance and a contact point which will not vary appreciably.

A feature of this invention is the arrangement of a contact clip in which a body portion surrounds the pin to which the clip connects. A spring tension then surrounds the body portion and a connection lead is riveted to the end of the body portion of the clip.

This invention is particularly adapted for making electrical contact to the plate tube pins of a high frequency vacuum tube which is similar to the RCA-832 and RCA-829.

In the prior art there are many different types of electrical connectors. However, such devices are not satisfactory for high frequency operation.

The characteristics which are highly desirable for a connection clip are as follows:

1. The tube clip should have low contact resistance and the contact point should not vary appreciably during operation.

2. The inductance of the tube clip should be low and the clip should make contact very near the glass seal to keep the lead inductance down.

3. The clip should be capable of operating at elevated temperatures without losing its holding qualities and should have good thermal conductivity so as to carry heat away from the tube seal.

4. The clip should be capable of being readily applied to the tube without tools.

5. The clip should be capable of operating satisfactorily over the range of pin diameters that may be encountered in a given type of tube.

6. The clip should not become loose under normal service or reasonable vibration and should be rugged for handling.

7. The clip should be simple in mechanical construction and easily manufactured and fabricated.

The device of this invention has the above requirements and has definite advantages over other types of tube clips when used for high frequency operation.

2

This invention will best be understood by referring to the accompanying drawing in which:

Fig. 1 is a perspective view of a contact clip of this invention,

Fig. 2 is a plan view of the contact clip,

Fig. 3 is an end view of Fig. 2,

Fig. 4 is a side view of Fig. 2,

Fig. 5 is an elevation shown partly in section of another embodiment of this invention, and

Fig. 6 is a plan view of Fig. 5.

Referring now to Figs. 1 to 4, inclusive, of the drawing, the tube contact clip of this invention comprises three major parts, namely, a body portion, a spring portion and a flexible connection strip. The body portion 1 is approximately rectangular in configuration and at the central portion thereof is drilled with an aperture 2 which provides clearance for the tube pin 10. The forward end of body 1 is rounded over, as shown at 3, and the top portion just beyond the rounded-over portion is a concaved portion slotted with a circular slot 4 which is cut through to meet the aperture 2. The rear portion of body 1 is drilled with two holes 5 to receive rivets 8. A

spring member 6 is made of material having good spring properties and good conductivity and will retain its properties at elevated temperatures of 300 degrees to 500 degrees Fahrenheit. Beryllium copper or spring steel silver plated has been found to be a suitable material. The spring 6 is secured to the lower portion of member 1 by rivets 8 and is bent around the curved front end thereof and continues on to a position substantially three-quarters around the curved portion 4.

A lead 7 is secured to the rear portion of body 1 and is riveted thereto by means of rivets 8. The lead 7 should be very flexible and possess good bending qualities and electrical and thermal conductivity. Beryllium copper or spring steel silver plated has also been found suitable for this lead. It is preferable that the lead 7 and spring contact member 6 be soldered with a high melting point solder. The tube clip and leads are preferably silver or copper plated for better electrical conductivity. In the operation of this device, it will be seen by referring to Fig. 1 that the portion of a vacuum tube 9 has an extending plate pin 10 located at the upper portion thereof.

When it is desired to make electrical connection to pin 10, a contact clip of this invention is forced

over pin 10 by pushing it through aperture 2. The length of pin 10 is such that the spring member 6 will be sprung out at the curved portion 4 and will tightly grip a substantial area of the tube pin and force the underside of pin 10 in good electrical contact within aperture 2.

The embodiment shown by Figs. 5 and 6 comprises a circular body portion 11 of metal which is slotted at 12 in a position just beyond the center as shown in Fig. 6. The central portion of member 11 is drilled at 13 for clearance of a tube pin similar to 10 which is mentioned above. The lower end of member 11 is counter-bored at 14. The sides of member 11 are cut away at 15 to form a clearance in which a spring member 16 of beryllium copper is located and, as seen in Fig. 6, the straight portion of spring 16 extends within the slot 12 to a distance just beyond the aperture 13, the arrangement being such that this portion of the spring will make contact to the tube pin 10. Just beyond the cut-away portion 15 there is shown a shoulder portion 17 against which a tubular cover member 18 is positioned. A flexible contact spring 19 is provided for making electrical connection and is joined to the lower portion of member 11 by being riveted or spun over at 20. By joining spring 19 to member 11 the cover 18 is retained.

In the operation of this device, the body portion 11 is forced over the end of tube pin 10 until the end opposite the strap 19 lies near the surface of the glass 22, thus forming a good positive connection to pin 10.

While we have indicated and described a system of our invention, it will be apparent to one skilled in the art that our invention is by no means limited to the particular devices shown and described, but that many modifications may be made without departing from the scope of our invention.

What we claim is:

1. An electrical connection device for making connections to the pins of a vacuum tube, comprising a body portion having a circular aperture arranged to extend along its length for the passage of one of said pins therethrough, said body portion having located on one of its sides a concaved portion which extends into the zone of said circular aperture, a spring tension device having an aperture therein which is positioned to register with the circular aperture in the body portion, said spring being secured to one end and fitted over one side of the apertured end and the concave side portion of said body portion, and a connection lead secured to said spring tension device and said body portion.

2. An electrical connection device for making an electrical connection to the pins of a vacuum tube, said device being particularly adapted for making an electrical connection to radio frequency apparatus, comprising a rectangular body having a rounded end portion and one concaved side portion, said rectangular body portion having a circular aperture at the rounded end portion for the passage of a connection pin of said vacuum tube, a spring tension device having an aperture therein which is positioned to register with the circular aperture in the body portion, said spring being secured to said body portion at an end opposite the rounded portion and extending along one side, over the rounded end and a part of the concaved side portion, and a connection lead secured to said spring and body portion.
3. An electrical connection device for high frequency use comprising a solid metallic rectangular body having a rounded end portion and a circular aperture extending inwardly therefrom, a concaved portion cut in one side of said body portion and arranged to bisect said circular aperture, a spring tension member having a circular aperture arranged to register with the circular aperture in the body portion, said spring tension member being secured to an end opposite said rounded end of the body portion, and fitted over the side and the periphery of rounded end of said body portion with its free end extending inwardly to the bisected portion of said cavity portion, and a flexible electrical connection strap secured to said body portion and said spring by the same securing means.
